TOBACCO PIPE

Filed Aug. 8, 1927

Patented Apr. 30, 1929.

1,710,850

UNITED STATES PATENT OFFICE.

DAVID A. WRIGHT, OF TAMPA, FLORIDA.

TOBACCO PIPE.

Application filed August 8, 1927. Serial No. 211,421.

This invention relates to smoking or tobacco pipes, and more particularly to pipes adapted to be used in either right-side-up or up-side-down position.

5 The objects of my invention are to provide a tobacco pipe of the character referred to consisting of few simple and inexpensive parts, which may be easily assembled or taken apart, for cleaning or renewing a worn or 10 broken portion, together with simple and efficient means for cleaning the pipe and for collecting and discharging or draining liquid or moisture therefrom, and means for producing a cooling effect upon the smoke in its 15 passage from the bowl to the mouth-piece and preventing the unpleasant or "biting" effect of hot smoke on the tongue or the roof of the mouth, or the entrance of nicotin or moisture and saliva into the mouth, and also 20 preventing the clogging up of the smoke channel while producing perfect combustion and more satisfactory results than are attainable with tobacco pipes as heretofore ordinarily constructed.

25 The invention will first be hereinafter more particularly described, with reference to the accompanying drawings, which are to be taken as a part of this specification, and then pointed out in the claims at the end of 30 the description.

In said drawings, Fig. 1 is a side elevation of a tobacco pipe embodying my invention; the bowl being shown in inverted position in full lines, while its upright position is indicated in dotted lines;

Fig. 2 is a longitudinal sectional view of the pipe shown in Fig. 1 in up-side-down position;

Fig. 3 is a longitudinal sectional view illustrating a modification of the invention;

Fig. 4 is a detail view of a broken-away portion of the bowl of the pipe shown in Fig. 3;

Fig. 5 is a vertical sectional view of another modification showing the bowl and stem of a pipe having a curved smoke channel;

Fig. 6 is a detail plan view of a broken-away end-portion of the mouth-piece; and

Fig. 7 is a side view of a preferred form 50 of spring with a nipple adjustably secured thereto.

Referring to said drawings, in which the same reference letters are used to denote corresponding parts in different views, the letter A, in Figs. 1 and 2, denotes the bowl with integral stem a and detachable extension a^1

which terminates in a preferably wide mouth-piece a^2 having several smoke ducts therein, though other forms may be used. The several parts mentioned are similar to corresponding parts of pipes of known construction and they are shown associated with co-operating elements embodying my invention, which I will now proceed to describe.

As shown, the bowl A is provided with a lining B which may be constructed of metal, preferably aluminum, and of cylindrical or conical form. To facilitate cleaning the pipe and to keep the smoke channel and the inlet thereto at the bottom of the bowl open and free from clogging matter, I insert in the smoke channel a resilient device of tubular form, preferably a spiral or coiled spring C, which extends through the stem a across the bottom of the bowl and has the convolutions thereof which are within the smoke channel in close contact, while the convolutions which are exposed within the bottom of the bowl are separated sufficiently to provide an intersticed construction adapted to permit air and smoke to pass freely therebetween into the inlet end of the smoke channel, while preventing the entrance of bits of tobacco or matter tending to close the same; thereby providing a spiral construction within the bowl through which air and smoke may enter the smoke channel, which is preferably larger than usual, and also providing a practically tubular body serving as a lining for said channel and forming a conduit connecting the bowl with a smoke and liquid receiving chamber D in the pipe stem, to receive nicotin and saliva or moisture drawn into the stem. The spring C extends entirely across the bottom of the bowl to the rear wall thereof and may be held against the bottom of the bowl when the pipe is in up-side-down position by the lining B abutting thereagainst at its lower end, as shown in Fig. 2. To the outer end of the spring C is secured, by soldering or otherwise, a disk or washer e, the periphery of which is soldered to or otherwise fixed within a sleeve or ferrule E, which connects the outer end of the stem a with the inner end of a mouth-piece or extension a^1 of the stem formed integrally with the mouth-piece a^2 . The disk or washer e, attached to the spring and ferrule, has a hole through the center thereof arranged in alignment with the smoke channel to permit the passage of smoke therethrough, and has secured thereto co-incident with said hole the larger end of

a tubular cone or nozzle C^1 , which provides a tubular extension of the smoke channel formed by the spring C . The sleeve or ferrule E spans the space between the stem and mouth-piece so as to provide a clear space around the cone or tubular tube C^1 and provide a chamber D to receive liquid or moisture exuding from the smoke channel. This channel, owing to the contacting convolutions 10 of the spring and the conical form of the nozzle C^1 tends to retard the flow of smoke through such channel, and in connection with the liquid chamber D , produces a cooling effect upon the smoke before it enters the extension of the smoke passage provided by the extension a^1 of the stem or the mouth-piece secured thereto. The liquid or moisture exuding from the smoke channel is collected in the liquid chamber D and may be discharged from time to time by either disconnecting the stem and ferrule or mouth-piece and shaking the moisture out of the stem or without disconnecting said parts, giving the stem a sidewise thrust so as to eject the moisture through the smoke passage in the mouth-piece. The open end of the bowl has secured thereto a cap or cover G , which is preferably hinged to the bowl at the stem side thereof and provided with a snap spring g on the opposite side in which there is a depression adapted to snap over a protuberance on the outer side of the bowl and thus prevent the cap or cover from becoming loose and dropping down so as to spill the burning tobacco 35 when the pipe is in the up-side-down position. The cap G is provided with numerous perforations for the admission of air, and within this cap is placed a body of reticular material such as wire netting, or the like, of circular or other form adapted to conform to the shape of the cap and having on the circumferential edge thereof a cylindrical flange, whereby it is properly spaced from the imperforate end-portion of the cap which forms the bottom of the bowl when the pipe is in up-side-down position, thus providing a false bottom for the bowl when in the latter position and a support therefor by which it is sustained above the imperforate bottom so as to provide an air chamber below the bowl when in up-side-down position and above the bowl when the pipe is in its normal upright position. In either position the operation of the pipe is very much like that of a stove, the wire netting or reticular material acting the same as a grate in a stove, and thus a good draft is insured, similar to the draft of a chimney. When the spring C is inserted in the stem a the sleeve or ferrule E , which is secured to the outer end of the spring, is forced over the end of the stem while the outer end of the sleeve fits tightly over the inner end of the extension a^1 of the stem or the mouth-piece so as in effect to unite the two parts as one, thus adapting the same to

serve as a handle for removing the mouth-piece and withdrawing the spring when it is desired to clean out the bowl and smoke channel. I thus provide a firm air-tight connection between the ferrule and extension of the pipe stem while at the same time the two parts are adapted to be forcibly disconnected.

In the form shown in Figs. 3 and 4 of the drawings, instead of a hinged cap or cover, the cap has its cylindrical body portion extended so as to overlap the bowl to which it is secured by means of a bayonet joint connection, as shown at I in Fig. 4; otherwise the construction of the cap is substantially identical with the cap previously described. Furthermore, in this modification, the exit end or terminal C^2 of the smoke channel formed by the spring C is of tubular form instead of the conical form shown in Fig. 2; otherwise the construction shown in Figs. 3 and 4 is substantially identical with the construction shown in Figs. 1 and 2. Preferably the outer end of the mouth-piece is flattened sufficiently to provide small ducts on opposite sides of an intermediate duct of larger size forming a continuation of the smoke channel through the stem, so that smoke is drawn in larger volume through the intermediate duct and a part caused to pass through the side ducts, which are very small in proportion to the size of the intermediate duct, so that the smoke issues from the mouth-piece in a divided stream instead of being concentrated and caused to issue through one large duct.

In the modification shown in Fig. 5 of the drawings, the pipe bowl A^2 is formed integrally with a curved stem a^4 having a smoke channel which is curved throughout its length, and in which is inserted a spring of the same construction as that described with reference to Fig. 2 of the drawings; the resiliency of the spring or equivalent device, such as a tube formed of wire netting or other reticular material, permitting the insertion thereof in a curved smoke channel.

Fig. 7 of the drawings illustrates a spring, such as shown in Figs. 2, 3 and 5, having adjustably attached thereto, at the delivery end of the smoke channel, a nozzle or nipple C^3 of elongated tubular form so as to provide at one side of the disk or washer e , a delivery or discharge end-portion c and on the other side a shank portion c^1 , the latter having formed thereon or secured thereto studs or pins c^2 , which are adapted to enter between adjacent convolutions or coils of the spring, in one end of which the shank portion of the tube is inserted, so that by rotating the nipple while the spring is held stationary, or vice versa, the studs or pins will be caused to move spirally following the coil of the spring while the nipple moves in the direction of the axis of the spring, either forward or back, according to the direction of rotation, thereby adjusting the spring so that it may extend a

greater or less distance into and across the bottom of the bowl as may be found desirable in practical use. In this instance the delivery end of the nipple or nozzle has secured thereto, by soldering or otherwise, a deflector or baffle plate c^3 , against which the smoke impinges as it passes out of the smoke channel into the liquid chamber D; said baffle plate having on opposite sides thereof rearwardly extending flaps or flanges c^4 which are soldered or otherwise secured to the tube so as to leave a narrow space between the discharge end of the nozzle and the baffle plate. As the smoke contacts with the baffle plate it is deflected or turned back into the liquid chamber wherein it is condensed and cooled, thereby producing a dry cool smoke; the moisture and nicotine being separated by contact with the baffle plate and caused to drip or drop down into the bottom of said liquid chamber.

In the preferred form of my invention I use the nipple of elongated tubular form having the deflector or baffle plate on its outer or delivery end, while its inner end is adjustably secured to the outer end of the coiled spring, but I do not desire to be limited to the particular form described, as other forms may be employed, and obviously the baffle plate may be attached to nipples of the form shown in Figs. 1 and 2, with or without the adjustable connection with the spring.

Having thus described my invention, what I claim as new and desire to secure by Letters Patent of the United States is:

1. In a tobacco pipe of the character described having a smoke channel extending through the stem, a coiled spring of tubular form extending through said channel into and across the bottom of the bowl; said spring having its convolutions in close contact within the smoke channel and spaced apart within the bowl.

2. In a tobacco pipe of the character described having a smoke channel extending through the stem and a liquid chamber at the outer end of the stem, a coiled spring of tubular form extending through said channel into and across the bottom of the bowl; said spring having its convolutions in close contact within the smoke channel and spaced apart within the bowl and having attached thereto at its outer end a tubular extension housed within said liquid chamber and adapted to discharge liquid or moisture therein.

3. A tobacco pipe having a smoke channel extending through the stem, a mouth-piece, a tubular connection between said stem and mouth-piece arranged so as to provide an intervening smoke and liquid receiving chamber, and a tubular resilient device extending through said smoke channel into and across the bottom of the bowl and having a nipple on its outer end protruding into said liquid chamber; said nipple having a baffle plate on

its discharge end, and said device being adapted to prevent bits of tobacco or the like from entering and clogging or closing the inlet to said smoke channel while permitting air and smoke to pass freely therethrough. 70

4. A tobacco pipe comprising, in combination, a bowl having a stem with a comparatively large smoke channel extending therethrough, a liquid chamber formed in an extension of the stem; said extension including a mouth-piece with a smoke passage therethrough, and a coiled spring extending through said smoke channel and having on its outer end a nozzle housed in said chamber; said nozzle having a baffle plate on its discharge end. 75

5. A tobacco pipe comprising, in combination, a bowl having a stem with a comparatively large smoke channel extending therethrough, a mouth-piece, a ferrule connecting said stem with said mouth-piece so as to form a liquid condensing chamber therebetween, and a coiled spring extending through said smoke channel and having on its outer end a nozzle housed in said liquid chamber; said nozzle having a baffle plate on its discharge end. 80

6. A tobacco pipe comprising, in combination, a bowl having a stem with a smoke channel extending therethrough, a coiled spring 95 extending through said channel and having on its outer end a nozzle housed in a liquid chamber formed in an extension of the stem, said extension comprising a mouth-piece and a ferrule detachably connecting said stem 100 and mouth-piece so as to form a liquid chamber therebetween.

7. A tobacco pipe having a stem with a smoke channel extending therethrough; said stem being provided with a detachable extension comprising a mouth-piece and a tubular coupling connecting said stem and mouth-piece so as to provide a moisture condensing and smoke receiving chamber therebetween; and a flexible tubular device extending 105 through said smoke channel into and across the bottom of the bowl and having at its outer end a nipple arranged to discharge smoke and moisture into said chamber. 110

8. A tobacco pipe having a stem with a smoke channel extending therethrough; said stem being provided with a detachable extension comprising a mouth-piece and a tubular coupling connecting said stem and mouth-piece so as to provide a moisture condensing 115 and smoke receiving chamber therebetween; and a flexible tubular device extending through said smoke channel into and across the bottom of the bowl and having at its outer end a nipple arranged to discharge smoke and moisture into said chamber; said nipple having a baffle plate on its free end adjacent the inlet to said mouth-piece. 120

9. In a tobacco pipe having a stem provided with a smoke channel therethrough, a mouth- 125

piece, and a tubular member connecting said stem and mouth-piece so as to provide an intervening smoke and moisture receiving chamber, a coiled spring extending from the bowl through said smoke channel and having on its outer end a nipple and means associated therewith for adjusting the spring so that it may extend a greater or less distance into the bottom of the bowl.

10. 10. A tobacco pipe having a stem with a smoke channel extending therethrough, a mouth-piece, a tubular connection between said stem and mouth-piece arranged to provide an intervening moisture receiving chamber, and a resilient device of tubular form extending through said smoke channel into and across the bottom of the bowl; said device having a nozzle on its outer end pro-

truding into said chamber, and said mouth-piece having at its inner end a cone-shaped cavity facing the discharge end of the nozzle.

11. A tobacco pipe having a stem with a smoke channel extending therethrough, a mouth-piece, a tubular connection between said stem and mouth-piece arranged to provide an intervening moisture receiving chamber, and a resilient device of tubular form extending through said smoke channel into and across the bottom of the bowl; said device having a nozzle on its outer end protruding into said chamber, and having a baffle-plate on its discharge end, and said mouth-piece having at its inner end a cone-shaped cavity facing the discharge end of said nozzle.

In testimony whereof I affix my signature.

DAVID A. WRIGHT.
